[57] CLAIM

The ornamental design for an emergency medical information container, as shown and described.

DESCRIPTION

FIG. 1 is a front elevation of my emergency medical information container showing my new design;

FIG. 2 is a left side elevation thereof, the right side elevation being a mirror image thereof;

FIG. 3 is a rear side elevation thereof;

FIG. 4 is a top plan view thereof, the bottom plan view being a mirror image;

FIG. 5 is an exploded view thereof; and

FIG. 6 is a section taken on line 6—6 in FIG. 3.

FIG. 1

FIG. 2

FIG. 3

FIG. 4

FIG. 5

FIG. 6
